ROLLER WEIR

Karl Schön, Wurzburg, Germany, assignor to firm
 Fried. Krupp Grusonwerk Aktiengesellschaft,
 Magdeburg-Buckau, Germany

Application October 3, 1933, Serial No. 692,046
 In Germany October 14, 1932

3 Claims. (Cl. 61—22)

This invention relates to roller weirs and more particularly to the runways upon which the roller weirs are designed to move. In comparison with floodgates which travel in a perpendicular direction, roller weirs have the disadvantage of requiring considerably greater pier lengths, which are necessitated by the inclined tracks upon which the rollers run. In order to overcome this disadvantage, attempts have been made previously to provide perpendicular runways for roller weirs also. In this construction, the resting point of the roller weir on the runways is considerably higher than that in the construction having inclined runways. As a result of this higher resting point in the vertical arrangement of the runways, a larger tractive force is necessary to raise the roller from its damming position, whereupon operating and winding mechanisms of substantially higher capacities are required.

It is the object of the invention to provide a roller weir in which the two disadvantages mentioned above are eliminated, in which the piers may be maintained proportionately short in the direction of the stream, and the force required to lift the roller weir from its damming position is no greater than that required in the case of an arrangement having inclined runways. These objects are attained by designing the runways so that the lower parts thereof extending within the field of the water current are inclined, and above the dammed water level, the runways pass suddenly or gradually into a steeper portion which may run perpendicularly or approximately so.

One embodiment of the invention is illustrated in the accompanying drawing which shows a sectional view of the roller weir with certain parts in elevation, in Fig. 1, and

Fig. 2 is a plan view of Fig. 1.

The roller weir 1 is shown in its damming position, having a beak-shaped damming plate 2 terminating in a jointed strip 3 resting on the bottom 4. The ends of the roller extend in recesses in the sides of the piers and are fitted at each end with a gear wheel 5 which engages with a toothed bar or track 6. These toothed bars, which constitute the runways of the roller, extend upwardly in an inclined direction at the lower ends thereof in the field of the water current and in the same direction as the water current. Above the dammed water level, the lower portion of each of the bars 6 passes through a circular arc, whose radius is suitably slightly greater than the radius of the gear wheel 5, and then into a steeper portion, the final direction of

which may be perpendicular or nearly so. For the purpose of lifting the roller, a raising means 7 is provided.

In the course of raising the roller from its damming position, it is necessary to overcome not only the weight of the roller, but also the force of the water pressure imposed thereon. The application point of the average force of the water pressure is known to be at approximately a third of the damming height and is illustrated by the arrow *x* in the drawing. The greater the difference in level between this application line and the points at which the roller rests on its runways, the greater is the force necessary to raise the roller. The numeral 8 in the drawing designates the resting points of the roller upon the runways in an arrangement in which the latter extend perpendicularly, as indicated in the dot and dash line in the drawing. By such an arrangement, a difference in level amounting to "a" exists between the resting points of the roller and the point of application of the average force of the water. Accordingly, in order to raise the roller in such a vertical arrangement of the runways, a tractive force is necessary which is determined by the distance "a", and which is proportionately large. On the other hand, according to the instant invention, in the inclined arrangement of the lower portions of the runways, the resting points of the roller are at 9, which results in a substantially smaller difference in level between these resting points and the above-mentioned point of application of the average force of the water. This difference in level "b", being substantially smaller than "a", requires a considerably smaller tractive force in order to raise the roller from its damming position. Since the force of the water pressure upon the roller weir decreases as the latter is raised, and at the position of the roller above the water surface, this force becomes equivalent to zero, it is possible for the runways to extend upwardly at about this point in a steeper direction, and finally they may run vertically in order to attain as short a pier as possible. The lengthening of the piers in the arrangement of the runways according to the instant invention in comparison with the lengths of the piers in which the runways extend vertically, results in a difference which is represented by the quantity *c* in the drawing, which for all practical purposes is insignificant.

Having described my invention, I claim:

1. In an apparatus of the class described, a roller weir adapted to dam a body of water, a runway for guiding said roller weir in the course of

- its being raised from its damming position, said runway extending upwardly in a direction inclined from the vertical at the lower portion thereof within the field of the water current and 5 in the same direction as the water current, and running in at least a nearly perpendicular direction, above the surface level of the dammed body of water.
2. In an apparatus of the class described, a 10 roller weir adapted to dam a body of water, a runway for guiding said roller weir in the course of its being raised from its damming position, said runway extending upwardly in a direction inclined from the vertical at the lower portion 15 thereof within the field of the water current and in the same direction as the water current, to lower the resting point of the roller weir upon said runway, said runway furthermore passing through an arc having a radius greater than that
- 20
- of said roller weir at about the surface level of the dammed body of water, and passing into a portion extending in at least a nearly perpendicular direction beyond that arc.
3. In an apparatus of the class described, a 80 roller weir adapted to dam a body of water, a pier at each end of said weir, a recess in each of said piers for guiding said roller weir, a gear wheel mounted on each end of said roller weir within each of said recesses, a toothed bar in each recess for carrying each of said gear wheels, each toothed bar extending upwardly sloping in a direction inclined from the vertical at the lower portion thereof within the field of the water current and in the same direction as the water current, and passing at about the surface level 85 of the dammed body of water into a portion which extends at least nearly perpendicularly.
- 90
